UNITED STATES PATENT OFFICE

2,373,300

CONDUIT CLIP

Herman Ray Ellinwood, Burbank, Calif., assignor
to Adel Precision Products Corp., a corporation
of California

Application March 20, 1943, Serial No. 479,955

5 Claims. (Cl. 174—40)

This invention relates to aircraft conduit supporting clips of the type shown in my United States Letters Patent No. 2,279,866 issued April 14, 1942, wherein an electrically conductive bonding strip is joined to the metal conduit-embracing strap as by being formed integral therewith and overlies the conduit-embracing cushion on the strap so as to contact the conduit embraced by the cushion to bond the conduit to the metallic structure of the aircraft through the strip and the strap.

The clip shown in the aforesaid patent is provided with an integral bonding strip which in one instance is struck out from the longitudinal mid-portion of the conduit-embracing part of the metal strap and protrudes through the cushion for contact with the conduit.

In another form of the clip of said patent the bonding strip is formed as a continuation of one of the ends of the strap, and in still another form the strip is struck out from the longitudinal mid-portion of the strap and extends over an end of the cushion without protruding through the cushion.

In the form in which the strip protrudes through the cushion the perforation of the cushion impairs the cushioning and insulating qualities thereof and the strap proper is objectionably weakened. In the form in which the strip is a continuation of an end of the strap it is necessary to double the end back on itself which requires an extra amount of material and adds objectionable bulk at the ends of the strap. In the form in which the strip is struck out so as to overlie the cushion without protruding through it, the strap is objectionably weakened.

It is the primary object of the present invention to provide a conduit clip of the character described in which the bonding strip is joined with and carried by the strap in such manner that the strap is not weakened, the conduit-engaging surface of the cushion is not perforated, objectionable bulkiness at the ends of the strap is avoided and but a relatively small additional amount of metal is required, with the advantages of appreciable simplicity of manufacture of the strap and in the assembly of the clip.

Another object of my invention is to provide an improved conduit clip of the character described in which the bonding strip is joined to a side or longitudinal edge of the strap intermediate the ends of the strap and disposed to overlie the conduit-engaging surface of the cushion, whereby the strap may be easily and inexpensively manufactured as a simple blank without weakening

the strap proper or appreciably adding bulk thereto and the operation of assembling the clip is simplified compared to clips having integral or otherwise strap-joined bonding strips as heretofore made.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a bottom plan view of a clip embodying my invention showing the strap, cushion and bonding strip as they appear before being bent into final form;

Fig. 2 is a cross sectional view taken on the line 2—2 of Fig. 1;

Fig. 3 is a top plan view of the assembly shown 20 in Fig. 1;

Fig. 4 is a cross sectional view taken on the line 4—4 of Fig. 3;

Fig. 5 is a top plan view of the assembly shown 25 in Fig. 3 with the bonding strip bent into position overlying the cushion;

Fig. 6 is a cross sectional view taken on the line 6—6 of Fig. 5;

Fig. 7 is a perspective view of a complete clip 30 as preformed to embrace a conduit;

Fig. 8 is a perspective view of the clip as installed.

Referring to the accompanying drawing, it is seen that a conduit clip embodying my invention includes a resilient metal conduit-embracing strap 1 having normally spaced apart opposed apertured ends 2 which are adapted to be brought together by means of a screw 3 to clamp the clip on a conduit 4 and secure it to a metal structural part 5 of an aircraft; a conduit-embracing cushioning member 6 of yieldable insulation material such as rubber, synthetic rubber, or the like, carried on the strap as a seat for the conduit, and an electrically conductive bonding strip 7 joined to a side edge of the strap and bent to overlie the conduit-engaging surface of the cushioning member for the purpose of "grounding" the conduit through the strap to the metallic structure of the aircraft.

As here shown the bonding strip 7 is formed 50 integrally with the strap 1, and is substantially L-shaped, with the shorter leg 7' joined to a side edge of the strap and normally extended outwardly at right angles thereto while the longer leg 7'' extends lengthwise of the strap in outwardly spaced and parallel relation to said edge.

In the forming of this integral bonding strip it is swaged or otherwise treated so that it will have considerably less thickness than the strap proper and constitute a very thin, narrow, flexible and slightly resilient bonding element which is bent 5 over a side edge portion of the cushion 6 to overlie the imperforate conduit-engaging face of the said cushion after the latter is applied to the strap as shown in Figs. 5 and 6.

After the bonding strip has been bent to cause 10 its longer leg 7" to overlie the cushion member as shown in Fig. 5, the assembly is bent to form a circular open loop and the strip 7 takes an arcuate form and lies in close conformity to the curvature of the cushion and strap as shown in Figs. 7 15 and 8.

As here shown the cushion 6 is of channeled cross section and provided with spaced opposed flanges 8 adapted to overlie the strap to hold the cushion thereon, the side edges of the looped portion of said strap being covered by said cushion except where the latter is cut away along a side edge thereof as at 9 to accommodate the strip 7.

With reference to Fig. 6 it is seen that the bonding strip 7 is bent at a point adjacent its joint with the strap 4, so as to form a curved portion 10 having a curvature of at least 170°. This provides a spring action in the bonding strip, relieves breaking stresses at the joint, makes for a smooth or flush bonding surface on the conduit-engaging face of the cushion, and prevents impairment of the cushioning action and damaging wear of the conduit where contacted with said strip. It is apparent that when the clip is clamped around the conduit the bonding strip will be forced into and become somewhat embedded in the yieldable cushion thereby providing the aforesaid "flush" seating of the bonding strip in the cushion member.

It should be noted that in joining of the bonding strip to a side edge of the strap at a point spaced inwardly from the ends of the cushion which has its ends spaced inwardly from the opposed ends 2 of the strap, and in bending the strip so that it overlies the cushion for contact with the conduit, it is unnecessary to perforate the conduit-engaging face of the cushion or to weaken the strap in any manner or produce bulkiness at the end of the strap. Moreover, the bonding strip in being formed integral with or otherwise joined to the strap at a side edge of the latter as above noted provides for a more direct and positive electrical connection between the bonding strip with the strap and insures a reliable bonding of the conduit to the metal structure of the aircraft, with less likelihood of disengagement of the bonding strip or the breaking thereof at its joint.

Also, it is to be observed that an advantage resides in the fact that the bonding strip, which is integral with the strap 4, extends for a short distance from a side edge of the latter in the same plane therewith and is then bent around an edge of said cushion and extends from its bent part into a terminal portion which lies within said cushion and in a bonding contact with the conduit, for this arrangement leaves the entire inner surface of the strap 4 in a direct gripping contact with the cushion.

While I have shown and described a specific embodiment of my invention I do not limit myself to the exact details of construction set forth,

and the invention embraces such changes, modifications and equivalents of the parts and their formation and arrangement as come within the purview of the appended claims.

I claim:

1. In a conduit supporting clip, a metallic conduit-embracing strap adapted to be secured to and in contact with a metallic structural part of an aircraft, a conduit-embracing cushion member of yieldable insulation material lining said strap, and a metallic bonding strip integrally joined to a side edge of said strap and extended from said joint over the cushion member for contact with the conduit seated on said cushion member, to bond the conduit to the strap.

2. In a conduit supporting clip, a metallic conduit-embracing strap adapted to be secured to and in contact with a metallic structural part of an aircraft, a conduit-embracing cushion member of yieldable insulation material lining said strap, and a metallic bonding strip joined to a side edge of said strap and extended from said joint over the cushion member for contact with the conduit seated on said cushion member, to bond the conduit to the strap, said bonding strip consisting of a thinned integral extension of a side edge portion of said strap.

3. In a conduit supporting clip, a metal conduit-embracing strap having opposed normally spaced apart apertured ends adapted to be brought together to clamp the strap around a conduit and provide for the fastening of said ends to a metallic support, a cushion member of yieldable insulation material lining said strap and providing a cushioned seat for the conduit, said cushion member having its ends spaced inwardly from the apertured ends of the strap, a metallic bonding strip of considerably less thickness than said strap, formed integral with a side edge of said strap at a point between the ends of said cushion member and being bent upwardly and inwardly to overlie said cushion member for contact with the conduit seated on said member.

4. In a conduit supporting clip, a metallic conduit-embracing strap adapted to be secured to and in contact with a metallic structural part of an aircraft, a conduit-embracing cushion member of yieldable insulation material lining said strap and covering the edges of the conduit embracing part thereof, and a metallic bonding strip integrally joined to a side edge of said strap and extended from said joint over the cushion member for contact with the conduit seated on said cushion member, to bond the conduit to the strap, said bonding strip having a bent portion where joined to the side edge of the strap, and said cushion being cut away at an edge thereof to accommodate said bent portion of said bonding strip.

5. In a conduit supporting clip, a metallic conduit-embracing strap adapted to be secured to and in contact with a metallic structural part of an aircraft, a conduit-embracing cushion member of yieldable insulation material lining said strap, and a metallic bonding strip joined integrally to a side edge of said strap from which it extends for a short distance in the same plane therewith and is then bent around an edge of said cushion and extends from its bent part into a terminal portion which lies within said cushion and in a bonding contact with the conduit.

HERMAN RAY ELLINWOOD.
